UNITED STATES PATENT OFFICE.

EDWARD H. ELLISON, OF JAMESTOWN, NEW YORK, ASSIGNOR TO MONARCH RE-FILLABLE FUSE CO., OF JAMESTOWN, NEW YORK, A CORPORATION OF NEW YORK.

KNIFE-BLADE FUSE.

Application filed April 27, 1920. Serial No. 376,931.

To all whom it may concern:

Be it known that I, EDWARD H. ELLISON, a citizen of the United States, residing at Jamestown, in the county of Chautauqua, State of New York, have invented certain new and useful Improvements in Knife-Blade Fuses, of which the following is a description, reference being had to the accompanying drawing, and to the figures of reference marked thereon.

This invention relates to knife blade fuses, and more particularly to that type in which the knife blades are aligned and held in fixed position in the ends of the casing by bridge pieces.

In fuses of the above character, the bridge pieces and casing ends have generally been provided with interlocking lugs and notches for preventing twisting of the bridge pieces relative to the casing while the fuse was being assembled. Such an interlocking connection presented a ready means of escape for the gases between these bridge pieces and the ends of the casing. Furthermore these bridge pieces which have been provided with registering open ended slots for the passage of the knife blades therethrough have never provided a smooth outer unbroken surface co-extensive with the areas of the casing about the knife blade whereby a felt washer could be uniformly pressed against said surface to provide a gas-tight joint. Another objection to this prior type of fuse has been due to the excessive number of detachable parts which have rendered the assembly of the fuse laborious and slow.

One of the objects of the present invention is to overcome the first-mentioned defect by providing a fuse of the above type having bridge pieces held in a predetermined position relative to the casing for aligning the knife blade terminals, wherein the end of the casing is smooth and unbroken against which the bridge pieces engage so that an effective gas-tight joint may be secured.

Still another object of this invention is to provide a fuse of the above character with bridge pieces held in a predetermined position relative to the casing and movable across the ends thereof into contact with

the knife blades to align and support the same.

Another object of the invention is to provide a fuse of the above type having bridge pieces held in a predetermined position relative to the casing and engaging against the smooth and unbroken ends thereof to effect a gas-tight joint, said bridge pieces extending completely across the end of said casing into contact with said knife blades to support and align the same and to entirely close the casing about said knife blades.

Another object of this invention is to provide a means for supporting the knife blades at each end of the casing which will entirely close the end of the casing about said knife blade so that the felt washer covering this closing means can be pressed by the end caps uniformly thereagainst throughout their entire area thus presenting a gas-tight joint around the projecting knife blade.

A further object of the invention is to provide a fuse of the above character in which these bridge pieces are supported by and close each end of the casing and have edges abutting and forming an opening for the knife blade, the bridge pieces being adapted to support each knife blade at points adjacent the casing walls, there being a projection on each knife blade adapted to support the bridge pieces centrally of said casing so that the bridge pieces are rigidly maintained in a plane parallel to the end of the casing and present a smooth unbroken surface about the knife blade against which the felt washer is pressed by the end cap.

An additional object of this invention resides in pivoting these bridge pieces to each end of the casing so that they may swing across into substantial contact with the knife blades and fit snugly therearound to form a closure for the casing end.

A further object of this invention is to reduce the number of detachable parts of a fuse of this character by permanently attaching the bridge pieces to the casing, and by non-detachably mounting the usual felt and metallic washers in the end caps.

Still another object of the invention is to provide a fuse end cap comprising an

open ended ferrule having metal and felt washers non-detachably carried thereby and apertured to permit the passage of the fuse knife blade therethrough, said washers being movable relatively to said ferrule to permit the assemblage of the fuse.

Another feature of the invention resides in providing a construction whereby the fusible link connected to the inner ends of the knife blade terminals within the casing is provided with an amperage mark on its outer end which projects with the knife blade through the gas-tight end of the casing outside of the end cap where it may be plainly seen.

These and other objects will in part be obvious and will in part be hereinafter more fully disclosed.

Referring more particularly to the accompanying drawings:

Fig. 1 is a side elevation of the fuse illustrating a portion thereof in cross section;

Fig. 2 is a cross sectional view of the same taken at right angles thereto;

Fig. 3 is an end view of the fuse with the end caps removed showing the knife blade in section fitting snugly between the bridge pieces;

Fig. 4 is a skeleton view of the knife blade terminals, the bridge pieces and the end caps;

Fig. 5 is a perspective view of the fusible link itself;

Fig. 6 is a sectional view showing a modification of the connections between the bridge pieces and knife blades;

Fig. 7 is a sectional view at right angles thereto;

Fig. 8 is an end view with the end caps removed;

Fig. 9 is a group view of the casing, bridge pieces, knife blades and end cap, and

Fig. 10 is a plan view of the casing with the bridge pieces in open position.

Referring more particularly to the accompanying drawings, the invention comprises the usual insulating casing 1, preferably threaded interiorly to receive therein metal end ferrules 2 projecting beyond the end of the casing and enlarged radially to provide a threaded surface 3 flush with the outer diameter of the casing. The metallic ends of this casing present smooth unbroken surfaces.

In order to align the knife blades 4 and 5 extending into each end of the casing, there are provided a plurality of bridge pieces 6 and 7 at each end thereof which are held in a predetermined relation to the casing, preferably by pivoting each one of them directly to the end of the casing. These pivotal connections may be loose and detachable from the casing, but preferably I provide the rivets 8 and 9 whereby the bridge pieces are

permanently pivoted to the casing ends. The form and outline of these bridge pieces may vary, one construction is shown clearly in Fig. 3 wherein they are provided with abutting edges, apertured or forming an aperture, snugly fitting about the knife blade passing therethrough. As will be seen, these bridge pieces swing into substantial contact with the sides of each blade to make a substantial fit therewith and close the end of the casing thereabout. As seen in Fig. 4 each knife blade where it contacts with the bridge pieces is undercut and narrowed to its inner end to provide shoulders or contact surfaces 10, 11, which directly engage the bridge pieces 6 and 7 near the annular end of the casing. By means of this construction, when the bridge pieces are swung into closed position about the knife blades, the same are aligned and held in fixed position relative to the casing.

In order to prevent these bridge pieces from sagging at the center especially when they are made of relatively thin metal, I provide each knife blade at the inner portion thereof with a laterally projecting metal ledge or stud 12 which as shown, projects from each side thereof in a plane substantially transverse to the plane of the knife blade and this stud is suitably spaced from the plane of the shoulder on the knife blade so that when the bridge pieces are swung into closed position they will be engaged by the same. Thus the bridge pieces are supported annularly by the end walls of the casing and in turn support the knife blades by means of the shoulders 10, 11 near the casing walls and the lateral projections in the rigid knife blades support the inner portions of the bridge pieces centrally of the casing.

The bridge pieces are held in closed position by means of the end caps 13, 14 which have internal threads 15 engaging the threads 3 on the ends of the casing 1. The outer ends of these caps are open and are provided with inwardly turned flanges 16 for non-detachably retaining the slotted metal washer 17 and the slotted felt or buck-skin washer 18, carried within said caps. Preferably the buck-skin washer is permanently attached to the inner face of the metal washer, as by gluing. By means of this construction, when the end caps 13 and 14 are screwed home on the ends of the casing, the outer metal washer 17 will press the inner felt or buck-skin washer 18, uniformly against and throughout the entire smooth outer surface of the bridge pieces 6 and 7 thereby effecting a substantially gas-tight joint at the end of the casing, while, at the same time, the bridge pieces are likewise clamped against the smooth unbroken ends of the casing, effecting a likewise gas-tight joint at this point.

The ends of the knife blades 4 and 5 projecting within the casing 1 are provided with the usual nut and bolt terminals 19 and 20 which are engaged by open ended slots 21 and 22 in the ends of the copper fusible link 23 so that the link may be detached without removing the nuts from the ends of the threaded bolt.

In order that the capacity of the fuse may be readily observable from without the casing, I preferably extend the end 24 of the fusible link 23 beyond the open ended slot 21 and provide the same with an amperage mark 25, such as 175^A. This end 24 of the fuse is preferably made flat to fit in a shallow similarly shaped recess 26 formed in the face of the knife blade 4, which recess extends from the inner terminal 19 along the length of the blade past the shoulders 10, 11 to a point which projects outside of the end cap when the same is tightly secured on the end of the casing so that the end 24 of the copper link 23 with the amperage mark 25 thereon will also project beyond the end of the casing where it can be plainly seen. By making the depth of the recess 26 equal to the thickness of the copper link terminal 25, the faces of the link and knife blade are preserved substantially flush so that the projection of the knife blade and fusible link through the bridge pieces 6 and 7 and end cap 13 is snug and prevents the escape of the gases therethrough.

It will be observed from Fig. 5 that the end 24 of the link 23 beyond the open ended slot 21 is suitably apertured as at 27 to pass over one of the laterally projecting lugs 12 on the knife blade.

In lieu of providing the knife blade with such a laterally projecting supporting lug 12, each knife blade may be suitably notched as shown in Fig. 7 to provide spaced shoulders 28 and 29 into which the bridge pieces 6 and 7 may swing for aligning and holding the knife blades in fixed position relative to the casing 1. In such event, the aperture 27 at the end 28 of the fusible link as shown in Fig. 5 is of course omitted. While any type of fusible link may be used in connection with my improved fuse, I prefer to use the link illustrated in Fig. 5 which I will not describe in detail inasmuch as it forms the subject of a separate application filed by me.

The various advantages of a fuse constructed as above are apparent. For instance, the pivoted bridge pieces will automatically align the blades when swung into closed position and will hold them assembled and positioned in the casing. The bridge pieces are held in place by the end caps which also press the felt washers tightly against the bridge pieces and hold the parts assembled against the outward force of the gases when the fuse is blown. If these

bridge pieces are made very thin and the metal liable to bend or flex when the cap is screwed home so as not to make a tight joint between the parts at the center of the blade, then the bridge pieces will be supported at the central portion of the casing by means of the laterally projecting studs on the knife blades, and these metal projections, if desired, may be set far enough out so as to engage the bridge pieces centrally before the edges of the bridge pieces are clamped tight against the casing, thus insuring a tight joint at the center, the ultimate purpose being to get the support for the bridge pieces which will hold them absolutely horizontal so that the metal end washer will clamp the buck-skin or felt washer both at the edges and centrally throughout the entire surface of the bridge pieces about the knife blade. Of course, as explained before, if these bridge pieces are made sufficiently heavy, these projections are not needed, and in the latter construction, the spaced shoulders at the edge of the knife blades will be used for holding them against endwise movement relative to the casing.

It will be obvious from the above that various minor changes in the details of construction and the arrangement of the parts may be made without departing from the spirit of the invention as set forth in the appended claims.

Having thus described the invention, what I claim as new and desire to secure by Letters Patent, is:—

1. A fuse comprising an insulating casing having substantially smooth unbroken ends, a fusible link therein, a projecting knife blade at each end thereof extending into and forming connections with the fusible link, means for closing the ends of said casing, bridge pieces for aligning said knife blades said bridge pieces engaging said smooth unbroken ends to secure an effective gas-tight joint, held in predetermined position relatively to said casing by means independent of said closing means.

2. A fuse comprising an insulating casing, a fusible link therein, a projecting knife blade at each end thereof extending into and forming connections with the fusible link, bridge pieces attached to the casing and held in a predetermined position relative to the casing and movable across the ends thereof into contact with said knife blades to align and support the same.

3. A fuse comprising an insulating casing having substantially smooth unbroken ends, a fusible link therein, a projecting knife blade at each end thereof extending into and forming connections with the fusible link, means for closing the ends of said casing, bridge pieces engaging said smooth ends to effect a gas-tight joint, said bridge

1. pieces extending completely across the end of said casing into contact with said knife blade to support and align the same and to close the casing about said knife blades and means independent of said closing means for holding the bridge pieces in predetermined position relatively to said casing. 70
2. A fuse comprising an insulating casing having smooth unbroken ends, a fusible link therein, a projecting knife blade at each end thereof extending into and connecting with the fusible link, bridge pieces held in a predetermined position relative to the casing and engaging said smooth ends to effect a gas-tight joint, said bridge pieces extending completely across the end of said casing into contact with said knife blade to support and align the same and to close the casing about said knife blades, said knife blades having central projections for supporting said bridge pieces centrally of said casing. 75
3. A fuse comprising an insulating casing, a fusible link therein, a projecting knife blade at each end thereof extending into and connecting with the fusible link, means attached to the casing and movable across each end of the casing into substantial contact with the knife blade to form a closed end for said casing, a felt washer covering said means, and an end cap engaging each end of said casing and pressing said washer against said means uniformly throughout the entire area. 80
4. A fuse comprising an insulating casing, a fusible link therein, a projecting knife blade at each end thereof extending into and connecting with the fusible link, means attached to the casing and lying in a single plane adapted to form a single opening in each end of said casing through which the knife blade projects and snugly fits, said means forming a smooth outer surface, a felt washer entirely covering said surface, and an end cap engaging said casing and clamping said washer uniformly against said means. 85
5. A fuse comprising an insulating casing, a fusible link therein, a projecting knife blade at each end thereof extending into and connecting with the fusible link, means attached to the casing and adapted to move across and form a single opening in each end of said casing through which the knife blade projects and snugly fits, said means forming a smooth outer surface, a felt washer entirely covering said surface, and an end cap engaging said casing and clamping said washer uniformly against said means. 90
6. A fuse comprising an insulating casing, a fusible link therein, a projecting knife blade at each end thereof extending into and connecting with the fusible link, means pivoted to each end of the casing and adapted to form a smooth outer surface through which the knife blade projects and snugly fits, said means forming a smooth outer surface, a felt washer entirely covering said surface, and an end cap engaging said casing and clamping said washer uniformly against said means. 95
7. A fuse comprising an insulating casing, a fusible link therein, a projecting knife blade at each end thereof extending into and connecting with the fusible link, means attached to the casing and adapted to swing across each end of the casing into contact with a knife blade to close the end of said casing, a felt washer covering said means, and an end cap engaging each end of said casing and pressing said washer against said means uniformly throughout the entire area. 100
8. A fuse comprising an insulating casing, a fusible link therein, a projecting knife blade at each end thereof extending into and connecting with the fusible link, means pivoted to the casing and adapted to close the ends thereof about the knife blades, a felt washer covering said means, and an end cap engaging each end of said casing and pressing said washer against said means throughout its entire area. 105
9. A fuse comprising an insulating casing, a fusible link therein, a projecting knife blade at each end thereof extending into and connecting with the fusible link, bridge pieces pivoted to each end of the casing and adapted to fit about the knife blade and close each end of the casing, a felt washer covering said means, and an end cap engaging each end of said casing and pressing said washer against said bridge pieces. 110
10. A fuse comprising an insulating casing, a fusible link therein, a projecting knife blade at each end thereof extending into and connecting with the fusible link, means connected to and completely closing each end of said casing and forming at their meeting edges an aperture fitting and positioning the knife blade passing therethrough, and end caps engaging said casing and clamping said means therebetween. 115
11. A fuse comprising an insulating casing, a fusible link therein, a projecting knife blade at each end thereof extending into and connecting with the fusible link, bridge pieces pivoted to each end of the casing and adapted to fit about the knife blade and close each end of the casing, a felt washer covering said means, and an end cap engaging each end of said casing and pressing said washer against said bridge pieces. 120
12. A fuse comprising an insulating casing, a fusible link therein, a projecting knife blade at each end thereof extending into and connecting with the fusible link, means attached to the casing and adapted to move across and form a single opening in each end of said casing through which the knife blade projects and snugly fits, said means forming a smooth outer surface, a felt washer entirely covering said surface, and an end cap engaging said casing and clamping said washer uniformly against said means. 125
13. A fuse comprising an insulating casing, a fusible link therein, a projecting knife blade at each end thereof extending into and connecting with the fusible link, means pivoted to each end of the casing and adapted to swing across each end of the casing into contact with a knife blade to close the end of said casing, a felt washer covering said means, and an end cap engaging each end of said casing and pressing said washer against said means uniformly throughout the entire area. 130
14. A fuse comprising an insulating casing, a fusible link therein, a knife blade at each end thereof extending into said casing and connecting therewith with the fusible link, means attached to the casing and adapted to move across and form a single opening in each end of said casing through which the knife blade projects and snugly fits, said means forming a smooth outer surface, a felt washer entirely covering said surface, and an end cap engaging said casing and clamping said washer uniformly against said means. 135

to swing across each end of the casing into contact with the knife blade to support the same in fixed position, and end caps engaging said casing for clamping said means therebetween.

15. A fuse comprising an insulating casing, a fusible link therein, a projecting knife blade at each end thereof extending into and connecting with the fusible link, means pivoted to each end of said casing for holding each knife blade in fixed relation, and end caps engaging said casing for clamping said means therebetween.

16. A fuse comprising an insulating casing, a fusible link therein, a projecting knife blade at each end thereof extending into and connecting with the fusible link, means pivoted to each end of said casing and forming at their meeting edges an aperture for fitting and positioning the knife blade passing therethrough, and an end cap engaging each end of said casing and clamping said means therebetween.

17. A fuse comprising an insulating casing, a fusible link therein, a projecting knife blade at each end thereof extending into and forming connections with the fusible link, each knife blade being provided with centrally arranged projections, and outer shoulders arranged in spaced parallel planes; bridge pieces pivoted to each end of said casing and adapted to swing between the planes of said projections and shoulders and

form interlocking engagement therewith, and an end cap engaging each end of said casing, and clamping said bridge pieces therebetween.

18. A fuse comprising an insulating casing, a fusible link therein, a projecting knife blade extending into each end thereof and connecting with the fusible link, blade supporting bridge pieces connected to and closing each end of said casing, an end cap including metal and felt washers connected thereto, means for preventing the detachment of said washers from said cap, passing over the end of each knife blade and engaging said casing to provide a substantially gas-tight packing for said casing end.

19. A fuse end cap comprising an open ended ferrule, a metal washer carried thereby and apertured to permit the passage of a fuse knife blade therethrough, means for retaining said washer in said ferrule, said means permitting the movement of said washer relatively to said ferrule.

20. An end cap for a fuse comprising an open ended ferrule provided with an inwardly projecting flange and interior threads, a metal washer loosely confined between said flange and threads, said washer being movable relatively to said ferrule.

In testimony whereof, I affix my signature.

EDWARD H. ELLISON.
